US0D1111635S

(12) **United States Design Patent** (10) **Patent No.:** **US D1,111,635 S**
(45) **Date of Patent:** **** Feb. 10, 2026**

(54) **VERSATILE OVEN**

(71) Applicant: **ILLINOIS TOOL WORKS INC.**,
Glenview, IL (US)

(72) Inventor: **Youliang Peng**, Guangdong (CN)

(73) Assignee: **ILLINOIS TOOL WORKS INC.**,
Glenview, IL (US)

(**) Term: **15 Years**

(21) Appl. No.: **29/930,960**

(22) Filed: **Mar. 4, 2024**

(30) **Foreign Application Priority Data**

Sep. 6, 2023 (CN) 202330577079.4

(51) **LOC (15) Cl.** **07-02**

(52) **U.S. Cl.**

USPC **D7/348; D7/347**

(58) **Field of Classification Search**

USPC D7/307, 323, 328-332, 337, 339-349,
D7/350.1-350.4, 352, 390, 402-409

(74) *Attorney, Agent, or Firm* — THOMPSON HINE LLP

(57) **CLAIM**

The ornamental design for the versatile oven as shown and described.

DESCRIPTION

FIG. 1 is a front perspective view of a first embodiment of the versatile oven in accordance with my new design;

FIG. 2 is a top perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is a front perspective view of a second embodiment of the versatile oven in accordance with my new design.

FIG. 10 is a top perspective view thereof;

FIG. 11 is a front view thereof;

FIG. 12 is a back view thereof;

FIG. 13 is a left view thereof;

FIG. 14 is a right view thereof;

FIG. 15 is a top view thereof;

FIG. 16 is a bottom view thereof;

FIG. 17 is a front perspective view of a third embodiment of the versatile oven in accordance with my new design.

FIG. 18 is a top perspective view thereof;

FIG. 19 is a front view thereof;

FIG. 20 is a back view thereof;

FIG. 21 is a left view thereof;

FIG. 22 is a right view thereof;

FIG. 23 is a top view thereof; and,

FIG. 24 is a bottom view thereof.

The broken lines shown in the Figures depict portions of the versatile oven that form no part of the claimed design.

1 Claim, 24 Drawing Sheets
